DESIGN FOR A TEXTILE FABRIC OR SIMILAR ARTICLE

Walter Speck, Haledon, N. J., assignor to Goldstein-Wilkins Corporation, New York, N. Y.

Application December 14, 1934, Serial No. 54,418

Term of patent 3½ years

To all whom it may concern:

Be it known that I, Walter Speck, a citizen of the United States of America, residing at 82 Church Street, Haledon, New Jersey, have invented a new, original, and ornamental Design for a Textile Fabric or Similar Article, of which the following is a specification, reference being had to the accompanying drawing, forming a part thereof.

The figure is a plan view of a textile fabric showing the complete width of the fabric to which my new design is applied, except for the portion

between the break lines which is similar to that on either side thereof. The dot and dash lines on the drawing outline substantially the design unit, which unit is repeated in regular succession as indicated by the extensions beyond the unit boundaries.

I claim:

The ornamental design for a textile fabric or similar article as shown and described.

In testimony whereof I have signed this specification.
